UNITED STATES PATENT OFFICE.

JAMES WILSON, OF STAMFORD, CONNECTICUT.

BATH-TUB CARRIER.

1,177,560.

Patented Mar. 28, 1916.

Application filed November 14, 1914. Serial No. 872,204.

To all whom it may concern:

Be it known that I, JAMES WILSON, a citizen of the United States, residing at Stamford, in the county of Fairfield and State of Connecticut, have invented new and useful Improvements in Bath-Tub Carriers, of which the following is a specification.

One object of this invention is to facilitate the handling of bath tubs, especially of the enameled type, so as to overcome the inconvenience encountered in carrying the tub to its place of installation, especially where it necessitates the carrying of the tub upstairs or through narrow passages.

A further object of the invention is the provision of a simple, strong, and durable carrying device, which may be expeditiously connected to and disconnected from the tub.

The invention further contemplates the provision of carrying means whereby the carrying operation may be readily performed by two persons.

Other objects of the invention will appear and be better understood from that embodiment of my invention of which the following is the specification, reference being had to the accompanying drawing forming a part thereof, in which—

Figure 1 is an end view of the bath tub, showing the tub tilted sidewise and the carrying device applied thereto. Fig. 2 is a side elevation of the tub in the position shown in Fig. 1. Fig. 3 is a perspective view of the carrying device showing one of the spacing knobs removed therefrom. Fig. 4 is a perspective view of one of the fingers.

Referring to the drawings in detail, the numeral 1 designates a bath tub of ordinary construction including the sides 2, 2, opposite ends 3, 3, rolled upper edge 4, and bottom 5, the latter having formed thereon at each end a pair of leg receiving sockets, each socket including a pair of spaced lugs 6 and 7, the opposing faces of which extend in converging relation toward the lugs forming the opposite socket and are adapted to receive therebetween the angularly extending tapering tongue 8 of the leg 9, the said leg being shown in dotted lines in Fig. 1.

The carrying or lifting device for the tub comprises an elongated handle member 10 which extends along one side of the tub the entire length thereof and is provided

with a pair of laterally extending tapering fingers 11, 11 which are adapted to fit in the lowermost sockets when the tub is tilted in the position shown in Fig. 1, and are integrally formed with sleeves 12, 12, which slidably embrace the member 10 so that the fingers may be adjusted toward or away from each other in order to permit the fingers to be inserted in sockets on tubs of different lengths. The fingers are held in their adjusted positions by means of set screws 13, 13 which pass through the sleeves at points diametrically opposite the fingers and are adjusted against the adjacent side 70 of the member 10.

In applying the carrying member to the tub, the latter is turned side-wise in the position shown in Fig. 1 and then rocked on the rolled edge until the lowermost edge 75 of the bottom is raised sufficiently to permit the fingers to be inserted in the lowermost sockets. The tub is then rocked in the opposite direction bringing the carrying member in engagement with the floor or other support for the tub. It will be noted that the opposite ends of the member 10 have removably associated therewith a pair of spacing knobs 14, 14, which, as shown in Fig. 1, are adapted to engage the floor and hold the member 10 in spaced relation thereto so as to permit the member 10 to be gripped by the hand.

From the structure above described, it will be manifest that the tub can be readily 90 carried by two persons each gripping the member 10 with one hand, while the rolled rim serves as a grip for the other hand, thereby permitting the tub to be readily lifted from the floor or other support and 95 conveniently carried to the place of installation.

Various changes in the form, proportions and minor details of construction may be resorted to without departing from the 100 principle or sacrificing any of the advantages of the invention as claimed.

Having thus described my invention, what I claim as new is:—

1. A bath tub carrier including a handle, fingers adjustably mounted on the handle and adapted to fit in the leg receiving sockets on the tub, and means for holding the fingers in adjusted position.

2. A bath tub carrier including a handle, fingers adjustably mounted on the handle and adapted to fit in the leg receiving

sockets on the tub, and means carried by the fingers and engaging the handle for holding the fingers in adjusted position.

3. A bath tub carrier including a handle, 5 tapering fingers adjustably mounted on the handle and adapted to fit in the leg receiving sockets on the bath tub, and means for holding the fingers in adjusted position.

4. A bath tub carrier including a handle, 10 fingers mounted upon the handle and adapt-

ed to fit in the leg receiving sockets on the tub, and knobs removably associated with the opposite ends of the handle.

In testimony whereof I affix my signature in presence of two witnesses.

JAMES WILSON.

Witnesses:

GEORGE R. CLOSE,
DOROTHY J. TILLEY.
